UNITED STATES PATENT OFFICE.

JACOB A. LEWIS AND WILLIAM G. SPIEGEL, OF NEW YORK, N. Y.

DESIGN FOR A MOLDED TIRE-SECTION.

SPECIFICATION forming part of Design No. 27,829, dated November 9, 1897.

Application filed September 22, 1897. Serial No. 652,661. Term of patent 7 years.

To all whom it may concern:

Be it known that we, JACOB A. LEWIS and WILLIAM G. SPIEGEL, citizens of the United States, residing at New York city, in the county and State of New York, have invented and produced a new and original Design for a Molded Tire-Section, of which the following is a specification, reference being had to the accompanying drawings, forming a part thereof, in which—

Figure 1 is a perspective view of the molded tire-section embodying the features of our design. Fig. 2 is a perspective view of the molded tire-section turned end for end, and Fig. 3 is a longitudinal section through the said tire-section.

The section of the tire is cylindrical and longitudinally curved, being of segmental shape, and at one end of the section a cylindrical projection is shown, the outer end whereof is flat. In the opposite end of the molded tire-section a circular recess appears.

We claim—

The design for a molded tire-section herein shown and described.

JACOB A. LEWIS.
WILLIAM G. SPIEGEL.
